(57) **CLAIM**

The ornamental design for a bayonet retaining rifle sight system, as shown and described.

DESCRIPTION

FIG. 1 is a side perspective view of the bayonet retaining rifle sight system in situ on a rifle;

FIG. 2 is a left side view of the bayonet retaining rifle sight system;

FIG. 3 is a right side view of the bayonet retaining rifle sight system;

FIG. 4 is a top view of the bayonet retaining rifle sight system;

FIG. 5 is a bottom view of the bayonet retaining rifle sight system;

FIG. 6 is a front view of a front component of the bayonet retaining rifle sight system;

FIG. 7 is a rear view of the front component of the bayonet retaining rifle sight system;

FIG. 8 is a front view of a middle component of the bayonet retaining rifle sight system;

FIG. 9 is a rear view of the middle component of the bayonet retaining rifle sight system;

FIG. 10 is a front view of a rear component of the bayonet retaining rifle sight system; and,

FIG. 11 is a rear view of the rear component of the bayonet retaining rifle sight system.

The broken lines in the drawings are included for the purpose of illustration only and form no part of the claimed design.
